UNITED STATES PATENT OFFICE.

FRANZ SOMMER, OF BERLIN, GERMANY.

IMPROVEMENT IN APPARATUS FOR PREVENTING INCRUSTATION IN STEAM-BOILERS.

Specification forming part of Letters Patent No. **154,921**, dated September 8, 1874; application filed June 29, 1874.

To all whom it may concern:

Be it known that I, FRANZ SOMMER, of Berlin, Germany, have invented an Improved Apparatus for Preventing Incrustations in Steam-Boilers, of which the following is a specification:

My invention relates to improvements in the reciprocating scraping or brushing apparatus employed in boilers for preventing the formation of incrustation; and consists in combining the brushes A with one or more movable frames, all as described hereafter, and as represented by the sectional elevation, Figure 1, sectional plan view, Fig. 2, and enlarged views, Figs. 3, 4, and 5, of the accompanying drawing.

The apparatus is intended especially for cylindrical boilers, and, in the present instance, it is applied to a boiler, B, communicating, through a leg, D, with a smaller boiler or mud-drum, B', all of which parts are arranged within a furnace, X, as indicated by dotted lines. Within the upper boiler, B, there is a metal frame-work, F, carrying the brushes A, the bristles of which are preferably constructed of wire; and in the lower boiler, B', there is a similar frame-work, F', also carrying brushes A, and connected to the upper frame-work by a rod, G, which extends through the leg D. The frame-work F is connected, by a rod, a, to a crank, H, on a vertical shaft, I, which extends through a stuffing-box, d, in the shell of the boiler, and which is operated by any suitable mechanism, (not shown in the drawing,) in such a manner as to impart a longitudinal reciprocating motion to the frame F and its brushes, and consequently to the lower frame, F', the connection with the latter, however, being such as to cause a less extended movement to be imparted to it than to the said upper frame. This continuous sweeping action of the brushes upon the interior of the boilers will effectually prevent the accumulation of

sediment and the formation of incrustations. The brushes may be arranged upon their frames in any suitable manner which will permit them to reach every portion of the shell of the boiler when reciprocated; but I prefer the arrangement illustrated in Figs. 3, 4, and 5, in which it will be observed that the separate brushes A A', &c., are secured at an angle to semicircular bars h of the frame, and that each brush has a squared stem, i, passing through the said bar h, and is acted on by a spring, k, which tends to force the brush outward against the shell of the boiler, but permits it to yield when drawn over the rivets and other inequalities in the interior of the latter.

I propose, in some instances, to so arrange the brush-holding frames and the operating mechanism that an oscillating, instead of a reciprocating, movement shall be imparted to the brushes.

I do not claim, broadly, a brush arranged within a boiler so as to be reciprocated therein; but

I claim—

1. The combination, with a boiler, of a frame within the boiler, carrying a series of brushes arranged at regular intervals apart, and a crank-shaft connected to the frame and operating the latter, as set forth.

2. The combination of the reciprocating brush-frame F and the brush-frame F', and its rod G, operated intermittently from the frame F, as set forth.

3. The combination of the reciprocating frame, brushes A, and springs h, as described.

In testimony whereof I have signed my name to this specification in the presence of two subscribing witnesses.

FRANZ SOMMER.
